Primary Examiner — Marianne Pandozzi(74) *Attorney, Agent, or Firm* — Wolf, Greenfield & Sacks, P.C.(57) **CLAIM**

The ornamental design for a beverage carafe, as shown and described.

DESCRIPTION

FIG. 1 is a top, front, right perspective view of a beverage carafe showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings is included for the purpose of illustration and form no part of the claimed design.
